Attorney

UNITED STATES PATENT OFFICE.

CLYDE UHL, OF BARTLESVILLE, OKLAHOMA.

HOISTING MACHINE.

Application filed January 31, 1920. Serial No. 355,458.

To all whom it may concern:

Be it known that I, CLYDE UHL, a citizen of the United States, and a resident of Bartlesville, in the county of Washington and State 5 of Oklahoma, have invented certain new and useful Improvements in Hoisting Machines, of which the following is a specification.

My invention relates to improvements in hoisting machines, it being more particularly a machine for hoisting or pulling the casing, tubing and rods from oil and gas wells, and it consists in the constructions, combinations and arrangements herein described and claimed.

15 The foremost object of my invention is to provide a combined hoisting machine and coupling, both being embodied in an automobile truck or similar vehicle, and so arranged that when the coupling is joined in 20 one way, the truck may be operated as such, and when the coupling is shifting into connection with the hoisting apparatus, the machine may be used for the purposes above specified.

25 Other objects and advantages will appear in the following specification, reference being had to the accompanying drawings, in which:—

Figure 1 is a side elevation of the improved machine, showing the coupling joined with the well tube hoisting apparatus,

Figure 2 is a side elevation of the hoisting drum and cooperating mechanism,

Figure 3 is a longitudinal section of the hoisting drum,

Figure 4 is an end elevation thereof,

Figure 5 is a cross section taken substantially on the line 5—5 of Figure 3,

Figure 6 is a detail perspective view of 40 the friction clutch head of the hoisting drum,

Figure 7 is a detail perspective view of the shifting lever,

Figures 8 and 9 are detail perspective views of the respective cooperating coupling members, and

Figure 10 is a detail sectional view showing how the cooperating coupling members are fastened together.

50 In carrying out my invention I provide a hoisting drum 1, which is mounted either upon the truck chassis 2, upon the frame of any ordinary tractor, or in fact, any vehicle which includes an engine by means of which 55 the drum 1 may be operated. Briefly de-

scribed, the vehicle in Figure 1 includes a transmission case 3, to the mechanism of which the drive shaft 4 is joined by means of the universal joint 5.

This drive shaft has a coupling plate 6, either integrally formed thereon, or otherwise applied, with a dove-tail wedge 7 (see Figures 8 and 10) to be fitted into the corresponding recess 8 in the companion coupling plate 9 of the driven shafts 10, 10^a.

When the coupling plate 6 of the drive shaft 4 is in connection with the plate 9 of the driven shaft 10, then the truck 2 is driven as such, that is to say, it is used as an ordinary automobile truck, the hoisting drum 1 then being out of operation. But when the coupling plates are unloosened, by removing the securing bolt 11, in Figure 10, and the coupling plate 6 fastened to the plate 9^a of the shaft 10^a, then the hoisting drum is reversed for operation to hoist oil or gas well casings, tubings and rods, or in fact, any other object which it may be desired to hoist.

There is a universal joint 12 in the shaft 10^a between the coupling plate 9^a and the differential gear case 13, on the exposed shaft 14 of which there is a sprocket 15 to which the drive shaft 16 is applied. This chain is also applied to the large sprocket 17 nearest the observer in Figure 1, which is carried by the drum shaft 18. The sprocket and chain mechanism just described, is duplicated on the other end of the drum shaft 18 as indicated in Figure 3 by the provision of the large sprocket 17 at the left end of the shaft.

Rollers or other suitable bearings 19, support the hoisting drum 1 on the shaft 18, it being observed that the shaft itself is journaled in bearings 20 and that the hoisting drum 1 is normally loose on the shaft. It is not until the clutch head 21 is forced inwardly by means of the lever 22, that the hoisting drum 1 is made to rotate with the shaft 18. The clutch head 21 at one end and a collar 23, fixed on the shaft at the other end, hold the hoisting drum in the proper position on the shaft.

The clutch head 21 carries paper-surfaced shoes 24 of suitable material, for engaging 105 the correspondingly surfaced recess of the drum as clearly shown in Figure 3. These shoes are resiliently held in place by means of the spring 25 in Figures 5 and 6. Connections 26 cause the clutch head to move 110

with the splined shifting collar 27 on the shaft 18 when the lever 22 is shifted as explained above.

Various positions of the hoisting drum are held by means of brake mechanism including the drums 28 on the ends of the hoisting drum 1, the brake bands 29 and the lever 30 which has proper connection 31 to both brake bands.

10 The operation may be reviewed to advantage. As stated above, the coupling plate 6 of the drive shaft 4 is ordinarily joined and secured to the corresponding plate 9 of the driven shaft 10, thereby causing the operation of the truck 2 as such. When this arrangement is effected, the truck may be driven about in the ordinary manner, the hoisting mechanism on top, at such times being inoperative.

20 When it is desired to use the apparatus for the purpose of hoisting, the bolts 11 is unloosened and the coupling plates 6 and 9^a secured together. By properly manipulating the levers 22 and 30, the hoisting drum 1 can be operated as desired. Of course at this time the truck 2 is practically a fixture, the truck being heavy enough to constitute an ample foundation for the operations of the hoisting drum.

30 It is to be clearly borne in mind that it is through the ability to shift the coupling of the drive shaft 4 into either of the two positions described, that it is possible to have the use of the automobile truck as such in one instance, and the use of an efficient hoisting mechanism in the other instance.

40 While the construction and arrangement of the improved hoisting machine and coupling mechanism is that of a generally preferred form, obviously modifications and changes can be made without departing from

the spirit of the invention or the scope of the claims.

I claim:

1. A vehicle including a driven shaft with 45 a coupling plate, and hoisting mechanism with drive gearing including a coupling plate; and a swingably mounted engine-driven shaft with a corresponding coupling plate, interchangeably connectible with 50 either aforesaid coupling plate, to operate either the vehicle or the hoisting mechanism.

2. A vehicle with a driven shaft having a coupling plate provided with a dove-tail recess, and a hoisting mechanism with drive 55 gearing including a shaft with a coupling plate having a dove-tail recess, and a swingably mounted engine-driven shaft, with a companion coupling plate having a dove-tail wedge insertible into the recess of either 60 coupling plate, with means for securing it, to drive either the vehicle or actuate the hoisting mechanism.

3. The combination, of an engine-driven shaft with a universal joint, and coupling 65 plate having a dove-tail wedge; a vehicle-carried driven shaft with a coupling plate having a dove-tail recess; and a hoisting mechanism drive shaft, with a universal joint and coupling plate with a dove-tail recess, the drive shaft coupling plate being secured to either of the latter coupling plates by fitting the wedge and recesses together. 70

4. A vehicle including a driven shaft with a coupling member, and hoisting mechanism 75 with drive gearing including a coupling member; and a swingably mounted engine driven shaft with a corresponding coupling member, interchangeably connectible with either aforesaid coupling member, to operate 80 either the vehicle or the hoisting mechanism.

CLYDE UHL.
